UNITED STATES PATENT OFFICE.

ALBERT HENRY MIDGLEY, OF ACTON VALE, ENGLAND, ASSIGNOR OF ONE-HALF TO
CHARLES ANTHONY VANDERVELL, OF ACTON VALE, ENGLAND.

PERCUSSION-FUSE FOR EXPLOSIVE PROJECTILES.

1,301,481.

Specification of Letters Patent.

Patented Apr. 22, 1919.

Application filed May 23, 1917. Serial No. 170,544.

To all whom it may concern:

Be it known that I, ALBERT HENRY MIDGLEY, a subject of the King of Great Britain and Ireland, and residing at Warple Way, 5 Acton Vale, in the county of Middlesex, England, have invented certain new and useful Improvements in and Relating to Percussion-Fuses for Explosive Projectiles, of which the following is a specification.

- 10 This invention relates to percussion fuses for explosive projectiles and more particularly for projectiles intended to be used with a smooth bore gun, such as a Stokes gun of the kind in which the striker and the cap 15 are carried by two separate blocks capable of axial movement relatively to each other and are kept in an inoperative position by a spring and a suitable member interposed between the two blocks.
- 20 It has previously been proposed in a percussion fuse in which the two pellets the blocks carrying the striker and the cap respectively are capable of axial movement relatively to each other, to keep the blocks 25 in an inoperative position by a safety member interposed directly between the striker and the percussion cap, said safety member being kept in its safety position by means provided inside the fuse holder and being 30 rotated therein by said means when the projectile is fired in order to remove the portion of the safety member lying directly between the striker and the percussion cap from such position.

- 35 The invention consists in arranging the safety member in a percussion fuse of the kind first above referred to, in such a position as to be directly interposed between the striker and the cap and retaining it in its 40 safety position by means provided outside the fuse holder. It will thus be seen that in the arrangement according to the present invention the rotation of the shell within the gun is not depended upon for the removal 45 of the safety member, such removal taking place during the flight of the shell through the air.

- The invention also consists in the provision of means for preventing the fuse being 50 assembled unless the safety member lies directly between the percussion cap and the striker, such means preferably consisting in the provision of a ridge and corresponding depression on the two blocks respec-

tively, the ridge being cut away where the 55 safety member has to be interposed between the cap and the striker.

The invention is illustrated by way of example in the accompanying drawings in which,

Figures 1 and 2 are two sectional elevations at right angles to each other, and

Fig. 3 is a sectional plan of the improved percussion fuse as intended to be used in conjunction with a projectile for a 65 Stokes gun.

Referring to the drawings, *a* is the holder of the percussion fuse which is formed with a conical seat *a*¹ and is preferably provided with a brass liner *a*², and *b* is a cover which 70 is formed with a conical seat *b*¹ arranged opposite the seat *a*¹ formed on the holder *a*. *c* is the block carrying the striker *d* and *e* is the block carrying the percussion cap *f*, both blocks being constructed in the form of 75 short truncated cones lodged in the conical seats *b*¹ and *a*¹ respectively and axially guided relatively to one another by a central guide *g* attached to the block *e*. The two blocks *c* and *e* are kept apart from each 80 other by springs *h* *h*¹, or by a spring which may be arranged to surround the central guide *g*. The striker *d* and the cap *f* are mounted eccentrically on the two blocks *c* and *e* respectively and a safety member *i* 85 is preferably constructed in the form of a sector is interposed between the two blocks. The safety member is arranged to lie between the striker and the cap, the part thereof which lies directly between the striker 90 and the cap being preferably formed with a depression *j* in order to receive the point of the striker *d* while still positively separating it from the cap *f*. The safety member may be retained in its position by means 95 of a tape *k* which is attached thereto at one end and is wound around the fuse holder *a* and secured thereto at its other end by means of a safety-pin *l* provided with a cord *l*¹ for facilitating its removal and engaging in 100 holes provided in suitable metal lugs *m* *m*¹ attached to the tape *k*.

Means are preferably provided for preventing the fuse being assembled unless the safety member is interposed directly between the 105 percussion cap and the striker. Such means may consist of a ridge *c*¹ provided on the block *c* and a corresponding depres-

sion e^1 formed on the block e , the ridge c^1 being cut away where the safety member is intended to lie between the two blocks viz., in the position between the striker d and the cap f .

The operation of the fuse hereinbefore described is as follows:—Before the projectile to which the fuse is attached is thrown, the safety pin l is removed by hand from the 10 holes in the metal lugs $m-m^1$ attached to the tape k . The rotation imparted to the projectile when thrown causes the tape to unwind itself and to be automatically removed from the fuse together with the safety member i attached thereto, whereby the projectile is rendered alive. Upon the projectile striking an obstacle endwise, either the block e carrying the striker moves toward the block e carrying the cap, or vice versa, according 20 to which end of the projectile strikes the obstacle. If the projectile strikes the obstacle sidewise the two blocks move toward each other by a kind of wedge action between the blocks and their conical seats.

25 I wish it to be understood that the details of construction may be varied without in any way departing from the spirit of the invention. For instance, the two blocks carrying the striker and the cap may be 30 kept apart from and be guided relatively to each other by other means than or by additional means to those above referred to; for example by means of a guiding pin n or a plurality of such pins. Likewise the safety 35 member may be constructed differently than in the manner above described.

What I claim is:—

1. A percussion fuse for explosive projectiles having a fuse holder, two separate 40 blocks capable of relative axial movement, a striker provided on one of the blocks, a percussion cap provided on the other block, a safety member arranged to lie directly between the striker and the cap and means 45 provided outside the fuse holder for retaining the safety member in its safety position, said means being a constituent part of the fuse and capable of becoming automatically disengaged from the fuse holder together

with the said safety member during the 50 flight of the projectile, as set forth.

2. A percussion fuse for explosive projectiles, having a fuse holder, two separate blocks capable of relative axial movement, a striker provided on one of the blocks, a 55 percussion cap provided on the other block, a safety member arranged to lie directly between the striker and the cap; a depression in the said safety member to receive the point of the striker while the striker is still 60 positively separated from the cap, and means provided outside the fuse holder for retaining the safety member in its safety position, said means being a constituent part of the 65 fuse and capable of becoming automatically disengaged from the fuse holder together with the said safety member during the flight of the projectile, as set forth.

3. A percussion fuse for explosive projectiles having a fuse holder, two separate 70 blocks capable of relative axial movement, a striker provided on one of the blocks, a percussion cap provided on the other block, a safety member arranged to lie directly between the striker and the cap, said safety 75 member being in the form of a sector, and means provided outside the fuse holder for retaining the safety member in its safety position, said means being a constituent part of the fuse and capable of becoming automatically 80 disengaged from the fuse holder together with the said safety member during the flight of the projectile, as set forth.

4. A percussion fuse for explosive projectiles having a fuse holder, two separate 85 blocks capable of relative axial movement, a striker on one of the blocks, a percussion cap on the other block, a ridge on one of the blocks with a portion cut away, a depression on the other block corresponding to the 90 said ridge, a safety member arranged to lie directly between the striker and the cap, and means provided outside the fuse holder for retaining the safety member in its safety position, as set forth. 95

In testimony whereof I have signed my name to this specification.

ALBERT HENRY MIDGLEY.
